Filed Mar. 18, 1957, Ser. No. 646,589

5 Claims. (Cl. 220—22)

This invention relates to improvements in Containers of the collector type, as shown in my prior Patent No. 2,464,441, granted March 15, 1949.

Containers of the type referred to have proven to be highly efficient and economical in serving the door-to-door collecting of refuse, either being towed by a truck or tractor or mounted on a hoisting unit of a vehicle. Such a container usually has a relatively large loading doorway at the rear thereof, with one or more doors for closing the same, and is made of sufficient size and capacity so that an attendant may reach or step into the container to deposit the refuse therein as it is being filled. Where the container is provided with wheels, as in the above-mentioned Patent No. 2,464,441, it can be moved along the street and, when loaded, pulled against the curb, to be picked up and dumped by the hoisting unit, after which it is deposited in a desired location for refilling.

In loading a container of the type mentioned, it has been found necessary for the attendant to walk forward into the container to begin the dumping of the material against the forward wall thereof. As he does this, the angle of repose increases with the height of the dumped material. As a consequence, the angle of repose has a tendency to prevent the attendant from stepping as far forward in the container as desired, without stepping on the collected refuse, so as to take full advantage of the entire loading space in the forward portion of the container. This is a difficulty which has long been experienced with such containers and not solved effectively heretofore.

One object of this invention is to overcome the objections noted as to the loading of collector-type containers, to enable the attendant to begin filling the container at the front thereof opposite from the filling door and without encountering an objectionable angle of repose to the material deposited in the container which would interfere with the filling operation.

Another object of the invention is to provide a collector-type container having an open side for retaining the material deposited therein within convenient reach of the attendant and without piling the material at an objectionable angle in the lower portion thereof which would interfere with the dumping action by the attendant.

Still another object of the invention is to provide suitable baffle means in a container of the collector type, or other suitable form of container, to hold the material in place therein as deposited and without permitting the material to fall at an objectionable angle in the lower portion of the container but to hold it effectively in place.

These objects may be accomplished, according to one embodiment of the invention, by providing an upstanding baffle plate in an intermediate portion of the container, and suspended therein substantially from end to end. The baffle plate preferably should be pivotally supported, so as to allow at least limited swinging movement.

2

It may be supported by brackets at opposite ends of the container, preferably with the upper edge of the baffle plate spaced downward sufficiently from the top of the container to allow the attendant to reach over the upper edge of the baffle for dumping the refuse into the forward portion of the container. The baffle plate should be held against substantial swinging movement, as by the provision of control stops in embracing relation with opposite sides of the baffle plate at each end thereof, which thereby allows some swinging movement of the baffle plate to prevent lodging of the material under the latter, as may occur if the baffle plate should be fixed, and yet the baffle is not free to swing to extreme positions, but will effectively retain the material in the forward portion of the container.

This embodiment of the invention is illustrated in the accompanying drawings, in which:

Fig. 1 is an end elevation of a container of the collector type, showing the invention applied thereto;

Fig. 2 is a detail cross section therethrough on the line 2—2 in Fig. 1;

Fig. 3 is a rear elevation of the container; and

Fig. 4 is a detail cross section through the baffle plate and supporting structure on the line 4—4 in Fig. 3.

The invention may be used in connection with many different forms and sizes of containers. For example, it may be used with a tilt-type container, as shown in the above-mentioned Patent No. 2,464,441, or in a drop bottom type of container, as illustrated herein. The size of the container likewise can be varied substantially. Usually such containers, especially when handling relatively light weight materials as trash and rubbish, are of relatively large capacity. Often the height of the container is sufficient to enable an attendant to walk upright or slightly crouched into the container to dump the material therein.

In the form of container illustrated, this is provided with a front wall, generally indicated by the numeral 1, opposite end walls 2 and a rear wall 3. The end walls

2 may be offset intermediate the height thereof, as shown in Fig. 2. These parts may be formed of suitable plates, welded or otherwise securely fastened together to form a rigid structure.

A bottom is indicated at 4. Any suitable form of bottom structure may be used as desired, but in the example illustrated in the drawings, the bottom 4 is formed as a sump and to provide a drop bottom door for discharging the contents from the container. The bottom 4 is hinged at 5 to the body of the container substantially at the lower edge of the front wall 1. Upstanding end wall sections 6 on the bottom 4 may be provided either to overlap the end walls 2 or to fit in notches therein, as conventionally provided in drop bottom containers. Lifting pins

7 are connected with these bottom sections 6, adapted to be engaged by lifting chains, cables or other fastenings or lifting means of a hoisting unit, as shown, for example, in my prior Patent No. 2,281,183, granted April 28, 1942, or by the arms of a fork truck for handling such containers in a manner now well understood in the art.

Also connected with the front wall 1 of the container is a bail 8, which may be pivoted thereto or otherwise connected, and of any suitable construction, for engagement by the hoisting means on the vehicle to facilitate dumping of the contents of the container.

The top of the container may be partially or entirely closed. A cover is shown at 9 and lids are provided extending partway over the top of the container and partway over the rear portion, as indicated at 10. These lids are hinged to the body of the container at 11. Counterbalance torsion springs may be connected with the hinge means, as indicated at 12, normally to return

the lids to closed positions. Latches are provided at 13 on the lids 10 for holding the lids securely closed.

The rear wall 3 covers a desired rearward portion of the container, while a substantial part of the rear thereof may be open for access by an attendant to the interior of the container. In addition to the lids 10, the rear wall opening may be provided with a pair of doors 14 of substantial size, so that when the doors and the lids 10 are open, the attendant may walk into the container to dump refuse therein. The doors 14 are hinged at 15 to the rear wall 3 and are provided with a latch 16 for holding the doors closed.

With a container of the walk-in type and size, it is preferred that a step be provided at the rear thereof, as indicated at 17 in Figs. 1 and 3. This step 17 is shown as hinged at 18 to the rear wall 3 on the body of the container and is limited in its downward swinging movement by chains 19 connected with the step 17. When not needed or after filling of the container, the step 17 may be turned to its upstanding position on the hinges 18, where it is retained in place by a latch assembly, generally indicated at 20.

Where the container is of the walk-in type, it has been customary heretofore for the attendant to step forward into the container and to dump the refuse adjacent the front wall thereof. The filling operation is started initially at the front wall. In order to prevent the refuse from falling at an angle of repose which would very quickly cover a major portion of the bottom 4 of the container, I have provided a baffle plate 21 upstanding in the lower portion of the container and extending substantially throughout the length thereof between the end walls 2, as will be apparent from Fig. 2. This baffle plate 21 may be formed of sheet metal of sufficient strength to retain the refuse in the forward portion of the container and is supported by a hinge rod 22, which may be in the form of a tube welded to the upper edge of the plate 21 and extending somewhat beyond the opposite ends thereof, as shown in Figs. 2 and 3. The opposite ends of the hinge rod 22 are received in bearing brackets 23 secured to the end walls 2, as will be apparent from Figs. 2 and 4.

This structure forms a pivotal support for the baffle plate 21, enabling it to swing about an axis extending lengthwise of the container at the upper edge of the baffle plate, as indicated in full lines and in dotted lines in Fig. 4. Stops or pins are provided preferably, as indicated at 24, on the end walls 2 intermediate the height of the baffle plate 21 for limiting the swinging movement of the baffle plate. It is sufficient that the stops 24 embrace the baffle plate at opposite ends thereof and need not extend throughout the length of the container. The baffle plate will thus be permitted to swing sufficiently to prevent lodging of the refuse under the lower edge thereof, as may occur if the baffle plate were fixed in the container.

In loading the container, the attendant usually steps on the step plate 17 and may walk into the container sufficiently to dump the material against the front wall. The attendant can step forward substantially to the baffle plate 21 and discharge the material over the upper edge of the baffle plate, without interference by material in the bottom of the container and without the necessity for stepping on refuse in the lower portion of the container, which may occur except for the baffle plate.

This will give a much better loading of the material and will not interfere in any way with the dumping, inasmuch as the baffle is suspended and can move either forward or rearward to a limited extent to free any large objects that might become trapped or wedged under the edge thereof, or to permit such objects to pass through the bottom opening. This dumping action may be accomplished in well known manners and especially as illustrated and described in my prior patent, No. 2,281,183, referred to above.

While the invention has been illustrated and described in one embodiment, it is recognized that variations and changes may be made therein without departing from the invention as set forth in the claims.

5 I claim.

1. A container of the character described comprising a body portion including opposite end walls and a front wall, a bottom structure hinged to the body portion and enclosing the bottom portion of the container, an upright baffle extending substantially between the end walls at a location intermediate the front and rear edges of said end walls, means pivotally suspending said baffle from said end walls for swinging movement about a horizontal axis remote from the bottom of said baffle, and means on an end wall extending into the path of swinging movement of the baffle and arranged to permit said baffle to swing freely through a restricted arc so as to prevent lodging of material with respect to the lower edge of the baffle and so as to permit loosening of objects during container dumping operations.

2. A container of the character described comprising a body portion including opposite end walls and a front wall, a bottom structure hinged to the body portion along a line parallel to said front wall and enclosing the bottom portion of the container, an upright baffle plate extending substantially between the end walls at a location intermediate the front and rear edges of said end walls, baffle support brackets on said end walls and extending inwardly therefrom, each of said brackets being substantially U-shaped and forming a seat, a horizontal support bar rigidly attached to the upper edge of the baffle plate and projecting beyond the opposite ends thereof, the projecting end portions of said bar being seated in said brackets to suspend said baffle plate for swinging movement, and fulcrum control stop members carried by the opposite end walls and extending inwardly in embracing relation with opposite sides of the baffle plate at each end of the baffle plate and being spaced apart to permit said baffle plate to swing freely through a restricted arc so as to prevent lodging of material with respect to the lower edge of the baffle plate and so as to permit loosening of objects during container dumping operations.

3. A container of the character described comprising a body portion including opposite end walls and a front wall, a bottom structure hinged to the body portion along a line parallel to said front wall and enclosing the bottom portion of the container, an upright baffle extending substantially between the end walls at a location intermediate the front and rear edges of said end walls, means pivotally suspending said baffle from said end walls for swinging movement about a horizontal axis remote from the bottom of said baffle, the bottom edge of said baffle being above and spaced from said bottom structure, and means on an end wall extending into the path of swinging movement of the baffle and arranged to permit said baffle to swing freely through a restricted arc so as to prevent lodging of material with respect to the lower edge of the baffle and so as to permit loosening of objects during container dumping operations.

4. A refuse container of the character described comprising a body portion including opposite end walls and front and back walls, a bottom structure hinged to the body portion and enclosing the bottom portion of the container, said back wall having an enlarged opening therein of such size as to permit an attendant to step into the interior of the rear portion of the container during the loading of refuse, an upright baffle extending substantially between said end walls, means pivotally suspending said baffle from said end walls for swinging movement about a horizontal axis remote from the bottom of the baffle, said baffle extending upwardly from a location near the bottom structure to a point spaced downwardly an appreciable distance from the top of the container to permit filling of the front portion of the con-

tainer over the top of said baffle, and means on an end wall extending into the path of swinging movement of the baffle and arranged to permit said baffle to swing freely through a restricted arc so as to prevent lodging of refuse with respect to the lower edge of the baffle and so as to permit loosening of objects during container dumping operations.

5. A refuse container of the character described comprising a body portion including opposite end walls and front and back walls and an enclosed top, a bottom structure hinged to the body portion and enclosing the bottom portion of the container, said back wall having an enlarged opening therein of such size as to permit an attendant to step into the interior of the rear portion of the container during the loading of refuse, an upright baffle extending substantially between the end walls at a location intermediate the front and rear edges of said end walls, means pivotally suspending said baffle from said end walls for swinging movement about a horizontal axis remote from the bottom of said baffle, said baffle extending upwardly from a location near the bottom struc-

10
